ASH TRAY

Frank B. Rosenberger, 6447 Hilltop Lane, Rte. 1,
Maumee, Ohio

Filed Sept. 18, 1959, Ser. No. 57,605

Term of patent 14 years

(Cl. D85—2)

FIG. 1.

FIG. 2.

FIG. 3.

FIG. 1 is a perspective view of an ash tray, embodying my new design;

FIG. 2 is a front elevational view; and

FIG. 3 is an end elevational view looking from the right of FIG. 2.

I claim:

The ornamental design for an ash tray, substantially as shown.
